ATTORNEY.

UNITED STATES PATENT OFFICE.

ALBERT A. GEHRT, OF QUINCY, ILLINOIS, ASSIGNOR TO THE COLLINS PLOW COMPANY, OF SAME PLACE.

BALING-PRESS.

SPECIFICATION forming part of Letters Patent No. 425,419, dated April 15, 1890.

Application filed February 1, 1889. Serial No. 298,416. (No model.)

To all whom it may concern:

Be it known that I, ALBERT A. GEHRT, of Quincy, in the county of Adams and State of Illinois, have invented a certain new and useful Improvement in Baling-Presses, of which the following is a full, clear, and exact description, reference being had to the accompanying drawings, forming part of this specification, and in which—

10 Figure I is a detail top view of a baling-press with the baling-chamber in section, illustrating my improvement. Fig. II is a similar view showing the parts in a different position. Fig. III is a detail side elevation.

15 My invention relates to the manner of forming the sweep-head in conjunction with the manner of connecting the pitman to the head; and my invention consists in features of novelty hereinafter fully described, and 20 pointed out in the claims.

Referring to the drawings, 1 represents the usual frame-work of a baling-press; 2, the baling-chamber; 3, the traverser; 4, the pitman, and 5 the sweep, loosely pivoted to the 25 frame-work by means of a vertical rod 7.

6 represents the sweep-head, also loosely pivoted to the rod 7, from which it projects in opposite directions. It is preferably so pivoted that it projects farther in the direction of the 30 pitman than in the direction of the sweep, or, in other words, it is preferably eccentrically pivoted to the frame of the press, with its longer end toward the pitman. The short end 8 is provided with lugs 9, leaving a recessed portion 10. In this recessed portion 35 works a pin 11, fitted in the sweep 5, the sweep preferably being bifurcated or forked at its inner end, as shown in Fig. III, so as to straddle the sweep-head. When the sweep is 40 moved in the direction indicated by the arrow in Fig. I the pin bears against one of the projections 9, and when the sweep is moved in the other direction it bears against the other projection 9.

45 The end 12 of the sweep-head is provided with a slot 13, preferably in the form of a horseshoe, or a shape approximating that of a horseshoe. In the slot 13 fits a friction-roller 14 on the outer end of the pitman 4,

and the pitman is thus connected to the 50 sweep-head.

The operation is as follows: The parts being in the position shown in Fig. I, the sweep is moved in the direction indicated by the arrow from the position shown in Fig. I to 55 the position shown in Fig. II. As it is thus moved, the outer face 15 of the slot 13 bears against the roller 14, and gradually forces the traverser to its forward position. As the traverser advances, the roller 14 approaches 60 the pivotal center of the sweep-head, and thus speed is converted into power, the movement of the traverser being rapid during the first part of the movement of the sweep, when little power is required, and being slow during the latter part of the movement of the sweep, when a great amount of power is required. As soon as the point of bearing 65 between the outer end of the pitman and the sweep-head passes the center line of the traverser or passes the position shown in Fig. II, the sweep-head will turn on its pivot from the position shown in full lines, Fig. II, to the position shown in dotted lines, thus allowing the traverser to rebound. Then the sweep is 70 moved in the other direction, (the pin 11 bearing against the opposite lug 9 to that which it bore against when the sweep was moved in the direction just described,) and the traverser will then be forced forward 75 again.

By constructing the machine in this manner there are very few parts, which at once affords cheapness in construction and little liability of getting out of order, and a machine thus constructed is also light and easily operated.

I claim as my invention—

1. The combination, with a traverser and a pitman, of a sweep-head formed with a slot 90 13 of horseshoe shape on one side of the pivot, and with lugs 9, forming a recess 10 on the other side of the pivot, and a sweep having a pin playing in the recess and bearing against the lugs, substantially as described. 95

2. The combination, with a traverser and a pitman, of the sweep-head formed with a slot 13, and with lugs 9, forming a recess 10,

and eccentrically pivoted to the frame-work of the press, and the sweep having a pin playing in the recess and bearing against the lugs, substantially as described.

5 3. The combination, with a traverser and a pitman, of a vertical rod 7, a sweep-head formed with a slot 13, and with lugs 9, forming a recess 10, and loosely pivoted to the rod,

and a sweep 5, loosely pivoted to the rod, and having a pin 11 playing in the recess and bearing against the lugs, substantially as described.

ALBERT A. GEHRT.

In presence of—

Wm. H. GOVERT,
LYMAN McCARL.
